DESIGN FOR A BABY BLANKET FASTENER

Harry Siegel, New York, N. Y., assignor to All-Best Specialties Corp., a corporation of New York

Application November 23, 1945, Serial No. 123,980

Term of patent 14 years

(Cl. D17—6)

To the Commissioner of Patents:

Be it known that I, Harry Siegel, a citizen of the United States, residing at New York, in the county of New York and State of New York, have invented a new, original, and ornamental Design for a Baby Blanket Fastener, of which the following is a specification, reference being had to the accompanying drawing, forming part thereof.

In the drawing, the figure is a perspective view of a baby blanket fastener, showing my new design, the opposite side of the design being plain.

I claim:

The ornamental design for a baby blanket fastener, as shown and described.

HARRY SIEGEL.
